Primary Examiner — George D. Kirschbaum*Assistant Examiner* — Joseph J Kukella(74) *Attorney, Agent, or Firm* — Sughrue Mion, PLLC(57) **CLAIM**

The ornamental design for a motorcycle tire, as shown and described.

DESCRIPTION

FIG. 1 is a perspective view of a motorcycle tire showing my new design;

FIG. 2 is a front view thereof;

FIG. 3 is a top view thereof;

FIG. 4 is a right side view thereof;

FIG. 5 is a left side view thereof;

FIG. 6 is a fragmentary enlarged front view;

FIG. 7 is a cross-section view taken along line 7-7 in FIG. 6; and,

FIG. 8 is a cross-section view taken along line 8-8 in FIG. 6.

The broken lines are used to show portions of the motorcycle tire that are not being claimed.

1 Claim, 8 Drawing Sheets(56)
